CLAIM

The ornamental design for a paint palette craft mat, as shown and described.

DESCRIPTION

FIG. 1 is a front, left, top perspective view of a paint palette craft mat, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a top plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 3;

FIG. 14 is an enlarged view of detail 14 in FIG. 4;

FIG. 15 is an enlarged view of detail 15 in FIG. 5;

FIG. 16 is an enlarged view of detail 16 in FIG. 7;

FIG. 17 is an enlarged view of detail 17 in FIG. 8;

FIG. 18 is a front, left, top perspective view of its enlarged scale in an alternate configuration;

FIG. 19 is an enlarged view of detail 19 in FIG. 18;

FIG. 20 is a front, left, top perspective view of the paint palette craft mat in a detached state;

FIG. 21 is an enlarged view of detail 21 in FIG. 20; and, FIG. 22 is an enlarged view of detail 22 in FIG. 20.

The dashed broken lines in the figures are for the purposes of illustrating portions of the paint palette craft mat and form no part of the claimed design.

The dash-dot-dash broken lines are for notating enlarged views and form no part of the claimed design.

1 Claim, 22 Drawing Sheets
